United States Patent Office

Des. 194,523
Patented Feb. 5, 1963

194,523

HANDBAG OR SIMILAR ARTICLE

Mamie L. Wooten, East Meadow, N.Y. (P.O. Box 668, Hq. Fifth Air Force, APO 925, San Francisco, Calif.)

Filed Apr. 3, 1962, Ser. No. 69,567

Term of patent 14 years

(Cl. D87—3)

FIG. 1 is a front perspective view of a handbag or similar article showing my new design;

FIG. 2 is a rear perspective view;

FIG. 3 is a side perspective view on a reduced scale, with the strap in connected position; and

FIG. 4 is a plan view on a similar reduced scale with the strap in disconnected position and the handbag laid out.

I claim:

The ornamental design for a handbag or similar article, substantially as shown.
